UNITED STATES PATENT OFFICE.

AUGUSTUS VIGNOS, OF CANTON, OHIO.

ATTACHMENT FOR PHOTOGRAPHIC CAMERAS.

SPECIFICATION forming part of Letters Patent No. 448,555, dated December 30, 1890.

Application filed February 10, 1890. Serial No. 339,776. (No model.)

To all whom it may concern:

Be it known that I, AUGUSTUS VIGNOS, a citizen of the United States, residing at Canton, in the county of Stark and State of Ohio, have invented certain new and useful Improvements in Attachments for Photographic Cameras; and I do hereby declare that the following is a full, clear, and exact description of the same, reference being had to the annexed drawings, making a part of this specification, and to the letters of reference marked thereon, in which—

Figure 1 is a view of the rear end of a camera, showing it open and the blinds entirely closed. Fig. 2 is a detached side view of the cut-out plate, showing the blinds properly attached and open. Fig. 3 is a transverse section through line xx , Fig. 2.

The present invention has relation to attachments to photographic cameras; and it consists in the different parts and combination of parts hereinafter described, and particularly pointed out in the claims.

Similar letters of reference indicate corresponding parts in all the figures of the drawings.

In the accompanying drawings, A represents the camera-frame, which is constructed in the ordinary manner and may be of any desired size.

The plate-holder B is located as illustrated in Fig. 1, and is constructed in the usual manner, reference being had to the size of the plate designed to be held.

The cut-out plate C is removably attached to the bars D, and is located substantially as shown in Fig. 1. This cut-out plate C is provided with the apertures a , which apertures correspond in size and form with the photographs desired to be produced.

In the drawings four apertures are shown; but it will be understood that a greater or less number may be used, if desired. It will be seen that if small photographs are to be produced the number of the apertures a may be increased, and if large-sized photographs are to be produced the number of the apertures will be decreased in proportion to the increase of the size of the photographs to be produced, regard being had that the same-sized camera is used in each instance.

The blinds E are held in the desired posi-

tions by means of the strips b, which are located as illustrated in the drawings, and are attached to the bars D by means of the screws 55 d or their equivalents. The bars D are provided with the ledges d', which ledges are for the purpose of receiving the edges of the cut-out plate C, as illustrated in Fig. 3.

It will be understood that the strips b should 60 be so adjusted that their inner portions will hug the blinds E, and thereby hold said blinds and the cut-out plate C at any desired point of adjustment.

In use the plate-holder B is placed in the 65 camera in the usual manner and the camera properly adjusted upon the object to be photographed, at which time the blinds E are so adjusted that but one aperture a will be open, when the negative is produced upon the negative-plate in the usual manner. The plate-holder B should be so adjusted that the first negative will be produced at one of the upper corners of the negative-plate proper, and when the first negative has been properly produced the plate-holder B, together with the negative-plate, is moved to the right or left 70 one of the stops f, at which time another negative is produced by the side of the first one produced, and so on until a full row of negatives have been produced across the top of the negative-plate, at which time the blinds E are so adjusted that the next lower or second aperture a will be open and the plate-holder B adjusted to the point it was when 75 the first negative was produced, and the second row of negatives produced, and so on until the negative-plate has been filled, or until the desired number of negatives have been produced.

It will be seen that the negative-plate may be filled with negatives taken from one object, or as many different objects as negatives desired to be produced.

It will be seen that by my peculiar arrangement I am enabled to produce any desired number of negatives upon one negative-plate with the use of one lens, and that one adjustment of the camera is all that is required for each horizontal row of negatives upon the 80 negative-plate proper.

For the purpose of holding the cut-out plate C in proper adjustment the plate F is provided, which is held in the desired position

by means of the notches g and the catches g' or their equivalent.

In the event the negative is to be larger than the original or object it will be under-

stood that a lens designed to enlarge should be adjusted in the camera, instead of a portrait-lens. In the event the negative is to be reduced in size the apertures a in the cut-out plate C are reduced in size and the camera to properly adjusted as to distance. It will also be understood that different cut-out plates C, having different-sized apertures, are used.

Having fully described my invention, what I claim as new, and desire to secure by Letters 15 Patent, is—

1. The combination of a photographic camera, the movable plate-holder B, the cut-out

plate C, provided with a series of apertures a , and the sliding blinds E, located against the cut-out plate C, substantially as and for the 20 purpose specified.

2. The combination of a photographic camera, the plate-holder B, the cut-out plate C, provided with a series of apertures a , the bars D, the strips b, the plate F, and the blinds E, 25 substantially as and for the purpose specified.

In testimony that I claim the above I have hereunto subscribed my name in the presence of two witnesses.

AUGUSTUS VIGNOS.
